UNITED STATES PATENT OFFICE.

GERALD S. FITZGIBBON, OF NIAGARA FALLS, NEW YORK.

GUARD FOR GRINDING WHEELS.

Application filed November 3, 1927. Serial No. 230,848.

The invention relates to a guard for emery and other grinding wheels.

It is well known that because of the high speed of rotation of grinding wheels, and especially emery wheels, the wheel is likely to break or explode and the flying pieces from the wheel endanger the operator as the pieces are thrown with great force.

This invention has for its principal object the provision of a guard to protect the operator from flying pieces of the grinding wheel should it break or explode, and that is automatically operated by the contact of the pieces flying from the wheel to close the guard downwardly and to hold it in a closed position to effectually stop the flying of pieces of the wheel in the direction of the operator.

The invention has for a further object the provision of a guard comprising a flexible upright which is adjustably mounted in an angular extension that is arranged over the upper part of the grinding wheel, the angular extension being adapted to be moved by impact of flying pieces of the wheel therewith downwardly by bending the flexible upright, a latch member being also provided to engage the angular extension when moved downwardly and hold it in such position to protect the operator.

The invention will be described in detail hereinafter and will be found illustrated in the accompanying drawings in which

Figure 1 is a side view in elevation of the improved guard showing it in relation with the grinding wheel,

Figure 2 is a front view in elevation,

Figure 3, a top plan view,

Figure 4, a horizontal sectional view on a plane indicated by the line 4—4 of Figure 1, and

Figure 5 a vertical sectional view on a plane indicated by the line 5—5 of Figure 1.

In the drawings similar reference characters will be used to designate corresponding parts throughout the several views.

The improved guard for grinding wheels is shown applied to a base 1, that may be a work bench or any other suitable support, and comprises a base member 2 secured to said base 1 by means of a bolt 3, and is provided with an upright flexible support 4 having a horizontally extending arm 5 provided with a longitudinal slot 6, 7 indi-

cates an angular member adjustably supported by the horizontal arm 5 by means of a bolt 8 engaging through slot 6, and including a downturned end 9. Horizontal arms 5 and angular member 7 are adapted to be arranged above the upper part of an emery or grinding wheel suggested at A, and the angular member 7 is secured in adjusted position by means of adjusting bolts 10 arranged on either side of the grinding wheel A. A tooth or projection 11 is secured to the inner side of the portion 9 adjacent to its lower end.

When the emery wheel A is in use and the work is being supported on a suitable work holder that is positioned at B, it will be understood that any pieces of the emery or other grinding wheel A that may be thrown tangentially of the upper side of the wheel will be intercepted by the angular member 7 and the downturned portion 9 and tooth 11 and the angular member will be driven forwardly and downwardly into the position shown in broken lines in Figure 1, the support 4 flexing or bending to permit such movement, and the operator standing at the work bench will be protected from the flying pieces of the wheel.

In order to drop the guard into the position described, and as shown in broken lines 85 in Figure 1, a latch member is provided comprising a flexible upright member 12 having an inturned projection 13 that engages the angular member when in dotted line position. Upright member 12 is provided with an upwardly and outwardly inclined portion 14 and its extremity inturned as shown at 15, said inclined portion 14 being engaged by the angular member 7 when moved downwardly by the flying 95 pieces of the emery or other grinding wheel to flex the member 12 to insure engagement of the inturned portion 13 therewith, while the inturned portion 15 serves as a stop to limit the upward movement of the arm 5 and angular member 7.

By having the angular member 7 adjustably secured to the arm 5 it will be apparent that said angular member may be arranged to guard wheels of varying diameters and to accommodate the guard to the grinding wheel as it is worn down by use.

A guard for the lower portion of the wheel is also provided and comprises a right angled member 16 having its base 17 pro-

vided with a longitudinal slot 18 that is engaged by one of the bolts 3.

What is claimed is:—

- 5 1. A guard for grinding wheels, comprising a flexible support, an angular member carried by said support and adapted to be arranged over a grinding wheel and to be engaged by pieces from the wheel and thereby move the member downwardly by bending the support, and means to hold the member in lowered position.
- 10 2. A guard for grinding wheels, comprising a flexible support, an angular member adjustably engaging said support and adapted to be arranged over a grinding wheel and to be engaged by pieces flying from the wheel and thereby moved downwardly by bending the support, and means to hold the member in lowered position.
- 15 3. A guard for grinding wheels, comprising a flexible support, a slotted arm extending from the support, an angular member carried by said arm and adjustable in the slot therein, said arm and member being adapted to be arranged over a grinding wheel and to be engaged by pieces flying therefrom and thereby moved downwardly by bending the support, and means to hold the member and arm in lowered position.
- 20 4. A guard for grinding wheels, comprising a flexible support, an angular member carried by said support and adapted to be

arranged over a grinding wheel, a projection on said member adapted to be engaged by pieces flying from the wheel and move 35 the member downwardly by bending the support, and means to hold the member and arm in lowered position.

5. A guard for grinding wheels, comprising a flexible support, an angular member 40 carried by said support and adapted to be arranged over a grinding wheel and to be engaged by pieces flying therefrom and thereby moved downwardly by bending the support, and a flexible latch member associated therewith and provided with a projection to engage said member and hold it in 45 lowered position.

6. A guard for grinding wheels, comprising a base, spaced uprights on said base, one 50 of said uprights being flexible and constituting a support, an angular member adjustably carried by the support and adapted to be arranged over a grinding wheel and to be engaged by pieces flying therefrom and thereby moved downwardly by bending the support, a flexible latch member associated therewith and provided with a projection to engage said member and hold it in lowered 55 position and the other of said uprights being adjustable on the base.

In testimony whereof I affix my signature.

GERALD S. FITZGIBBON.
